D. P. POWER.

DEHYDRATOR OR DRIER.

APPLICATION FILED JUNE 21, 1921.

1,422,620.

Patented July 11, 1922.

UNITED STATES PATENT OFFICE.

DUDLEY P. POWER, OF PORTLAND, OREGON, ASSIGNOR OF ONE-THIRD TO EVERETT P. BABCOCK AND ONE-THIRD TO FRANK DELANO, BOTH OF PORTLAND, OREGON.

DEHYDRATOR OR DRIER.

1,422,620.

Specification of Letters Patent. Patented July 11, 1922.

Application filed June 21, 1921. Serial No. 479,218.

To all whom it may concern:

Be it known that I, DUDLEY P. POWER, a citizen of the United States, and a resident of the city of Portland, county of Multnomah, and State of Oregon, have invented a certain new and useful Improvement in Dehydrators or Driers, of which the following is a specification.

The object of my invention primarily is to bring about an efficient drying of fruits and vegetables, by causing currents of air to pass over trays, first in one direction for a predetermined period, and then in the reverse direction; the circulated air being previously heated so as to be better adapted to carry off a larger amount of moisture.

A further object of my invention is to make the operating devices automatic so that, by suitable means, the movement of the air current through the drying chamber will be periodically reversed, and, in time with such reversal, the gates controlling the admission of the exterior air, to be moved through the drying chamber, will be opened and closed as required, and the action of devices by which the movement of the air is accomplished will be correspondingly controlled.

A further object of my invention is to provide for the exterior air to be moved through the stack of perforated trays both in perpendicular column, and in strata passing over and between the trays.

I attain the features above specified, and others incidental thereto, by the devices illustrated in the accompanying drawing, which shows in diagrammatic form a vertical section of my dehydrator, and the operating devices and means thereof.

I have not detailed the operating parts, and operating means since such details may be left to the discretion of the builder of my dehydrator, so long as he follows the principle of operation hereinafter described, towards which the construction of my dehydrator must be directed.

a represents the housing of my dehydrator having doors *b*, *c*. The drying chamber *d* of the housing is provided with legs *e* supporting a stack of horizontal trays *f*, the bottoms of which are perforated or may be made of wire cloth. The top and bottom ends of the drying chamber are open and on such ends are mounted domes *g* and *h* and the so enclosed space provides ante-chambers *i* and *j*. The ante-chambers have ports *k* and

l, communicating with the exterior air. The passage of the air through said ports is controlled by gates *m* and *n* which may consist of a series of plates or leaves pivoted so as to overlap in one position and thus close the passage way as shown by the gate *m* or for being opened as shown by the arrangement of the gate *n*. The leaves are connected to rods *o* and *p* and such rods are connected to bell cranks *q* and *r*; these devices being so arranged that the movement of the rods *o* and *p* in one direction opens the gates *m* and *n* respectively, and movement in the opposite direction closes said gates.

On one side of the housing *a* is provided an air passage way *s* in which is a heating coil or pipe which in practice is connected with heating means for example a steam boiler, the connection from the steam boiler being effected with the termini *u* and *v*.

Gates *w* and *y* control the inlet ports *x* and *z* of the passage way *s*. The gates are connected by a rod *3* and by other rods *4* and *5* with the bell cranks *q* and *r* so that by moving the doors to open first one and then the other of the ports *x* and *z* of the passage way *s* the bell cranks *q* and *r* are correspondingly operated and through the latter by the rods *o* and *p* the gates *m* and *n* are correspondingly operated.

The doors are opened and closed as mentioned by a screw shaft *6* the thread of which actuates a slide *7* having a projecting contact member *8* adapted to engage with the pins *9* and *10* of the doors *w* and *y* and thus open and close the latter in accordance with the direction in which the screw shaft *6* is driven.

The screw shaft *6* is rotated first in one direction and then in the other periodically by the means diagrammatically shown at *11* consisting of a train of bevel gears, two of which are adapted to idle on the shaft *12* until connected with the shaft through the medium of a clutch, the element *13* of which is moved by an arm *14* carrying a weighted arm *15* to hold the arm *14* steadily; and the arms *14* and *15* are operated by a rod *16* connected to a bell crank *17* operated in a groove *18* of a peripherally grooved shaft *19* operated by suitable means engaging the bevel pinion *20* carried by the shaft *19*.

In the open ends *k* and *l* of the ante-chambers *i* and *j* are suction fans *21* and *22* driven by motors *23* and *24* and belts *25* and *26*,

the motors being electrically operated, the circuit wires being represented at 27 and 28; the electric circuit being opened and closed through the medium of switches 29 and 30 5 operated by the bell cranks *q* and *r*.

The ends of the passage way *s* are connected with the ante-chambers *i* and *j* respectively through conduits 31 and 32. The passage of air through said conduits is controlled by butterfly valves 33 and 34 operatively connected with the bell cranks *q* and *r*.

Between the ante-chambers *i* and *j* and the open ends of the drying chamber *d* are provided screens 35 and 36 having air directing vanes 37 and 38 on the interior; the screens 35 and 36 functioning to distribute the air more uniformly throughout the drying chamber.

An auxiliary air passage way 39 extends 20 from one to the other of the ante-chambers *i* and *j* and such auxiliary passage way has ports 40 located between the trays *f* which are spaced apart; the ports 40 functioning to inject horizontal strata of air between the trays. The ends of the auxiliary passage way are controlled by gates 42 which may be similar in construction to the gates *m* and *n* and they are operatively connected by devices 43 and 44 with the bell cranks *q* 25 and *r* respectively so as to be opened and closed by the movement of the latter.

In order to prevent dust or foreign particles from being carried by the air currents into the interior of the dehydrator I prefer 30 to cover the ends of the passage way *s* communicating with the conduits *u* and *v* by screens 45 and 46.

The operation of my dehydrator is as follows: In the position of the parts shown the 40 screw shaft 6 has just operated to close the upper gate *w* and open the lower gate *y* of the passage way *s* thus permitting the air to enter the bottom end of the passage way *s* as indicated by the arrows, the air becoming heated in its passage over the heating coils *t* so as to be rendered in better condition for absorbing moisture. Simultaneously the gate 33 has been opened so that the heated air may flow through the conduit 45 31 into the ante-chamber *i* and simultaneously the switch 30 has been closed so as to set the motor 24 into operation and thereby rotate the suction fan 22. At the same time the gate *m* has been closed and the gate *n* 50 opened and the butterfly valve 34 in the conduit 32 has also been closed. Hence the heated air currents will be drawn through the drying chamber as indicated by the arrows toward the lower end of the drying chamber and expelled through the port 1 at the bottom of the dehydrator to the atmosphere. Furthermore, the crank arms *q* and *r* have functioned to open and close the gates 55 41 and 42 of the auxiliary passage way 39 thereby permitting some of the air currents

to pass into said auxiliary passage way 39 and to be emitted from the latter through the ports 40 and horizontal strata by the trays *e*.

The devices are so arranged that the 70 switches 29 and 30 will be alternately opened and closed and the gates likewise operated through the medium of the devices rotating the screw shaft 6, such devices being timed to rotate the screw shaft for definite periods 75 in alternate directions; and thus the direction of the movement of the air currents through the drying chamber will be alternated. Other uses of my invention than the use above specified will be self suggesting. 80

While I have spoken of both fans *m* and *n* as suction fans, of course, one of these fans could be operated as a blower, if desired, and both fans then operated together in such case, one pushing and the other pulling 85 the air through the drying chamber.

Since my dehydrator is specifically designed for using air as the drying medium I have used that term in the claims but in other uses of my invention the term air is 90 to be understood as synonymous with any gas or gases.

I claim:

1. A dehydrator or drier comprising a 95 drying chamber, an ante-chamber at each end of the drying chamber, such ante-chambers communicating on one side with the exterior of the drying chamber and on the other side with the exterior air, gates controlling the exterior air ports of said ante-chambers, fans adapted to cause currents of air to pass through said ante-chambers and said drying chamber, means for preheating the air admitted into said ante-chambers, automatic means adapted to operate said 100 gates relatively to the predetermined movement of the air, and in time therewith to control the action of the devices for effecting the movement of the air through said drying chamber, the means controlling the 105 air moving devices being adapted to reverse the latter at predetermined periods.

2. A dehydrator or drier comprising a 110 drying chamber, an ante-chamber at each end of the drying chamber, such ante-chambers communicating on one side with the exterior of the drying chamber and on the other side with the exterior air, gates controlling the exterior air ports of said ante-chambers, fans adapted to cause currents of 115 air to pass through said ante-chambers and said drying chamber, an elongate air passage way connecting said ante-chambers with the exterior air, gates controlling the admission of air from the exterior into said 120 passage way, the latter gates being located at the opposite ends of said passage way, other gates controlling the admission of air from said passage way into said ante-chambers respectively, means for heating the air 125

in said passage way, and automatic means adapted to operate said gates relatively to the predetermined movement of the air, and in time therewith to control the action of the 5 devices for effecting the movement of the air through said drying chamber.

3. A dehydrator or drier comprising a drying chamber, an ante-chamber at each end of the drying chamber, such ante-chambers 10 communicating on one side with the exterior of the drying chamber and on the other side with the exterior air, gates controlling the exterior air ports of said ante-chambers, fans adapted to cause currents of 15 air to pass through said ante-chambers and said drying chamber, an elongate air passage way connecting said ante-chambers with the exterior air, gates controlling the admission of air from the exterior into said 20 passage way, the latter gates being located at the opposite ends of said passage way, other gates controlling the admission of air from said passage way into said ante-chambers respectively, means for heating the air 25 in said passage-way, automatic means adapted to operate said gates relatively to the predetermined movement of the air, and in time therewith to control the action of the devices for effecting the movement of the air 30 through said drying chamber, the means controlling the air moving devices being adapted to reverse the latter at predetermined periods.

4. A dehydrator or drier comprising a 35 drying chamber, an ante-chamber at each end of the drying chamber, such ante-chambers communicating on one side with the exterior of the drying chamber and on the other side with the exterior air, gates controlling the exterior air ports of said ante-chambers, fans adapted to cause currents of 40 air to pass through said ante-chambers and said drying chambers, air distributing means between said ante-chambers and the drying 45 chamber, means for preheating the air admitted into said ante-chambers, and automatic means adapted to operate said gates relatively to the predetermined movement 50 of the air, and in time therewith to control the action of the devices for effecting the movement of the air through said drying chamber.

5. A dehydrator or drier comprising a 55 drying chamber, an ante-chamber at each end of the drying chamber, such ante-chambers communicating on one side with the exterior of the drying chamber and on the other side with the exterior air, gates controlling the exterior air ports of said ante- 60 chambers, fans adapted to cause currents of air to pass through said ante-chambers and said drying chambers, air distributing means between said ante-chambers and the drying 65 chambers, an elongate air passage way connecting said ante-chambers with the exterior

air, gates controlling the admission of air from the exterior into said passage way, the latter gates being located at the opposite ends of said passage way, other gates controlling the admission of air from said passage way into said ante-chambers respectively, means for heating the air in said passage-way, a screen in each end of said air passage way, through which the air passes from the latter into the adjacent ante-chamber, and automatic means adapted to operate said gates relatively to the predetermined movement of the air, and in time therewith to control the action of the devices for effecting the movement of the air 70 through said drying chamber.

6. A dehydrator or drier, comprising a drying chamber, a stack of perforated trays therein, an ante-chamber at each end of the drying chamber, such ante-chambers communicating on one side with the exterior of the drying chamber and on the other side with the exterior air, gates controlling the exterior air ports of said ante-chambers, fans adapted to cause currents of air to pass 75 through said ante-chambers and said drying chamber, an elongate air passage way connecting said ante-chambers with the exterior air, gates controlling the admission of air from the exterior into said passage way, the latter gates being located at the opposite ends of said passage way, other gates controlling the admission of air from said passage way into said ante-chambers respectively, an auxiliary air passage connecting 80 said ante-chambers and provided with air ports between the trays into the drying chamber, gates in the ends of the auxiliary passage way adapted to control the passage of air therethrough, and automatic means 85 adapted to operate said gates relatively to the predetermined movement of the air, and in time therewith to control the action of the devices for effecting the movement of the air 90 through said drying chamber.

7. A dehydrator or drier, comprising a drying chamber, a stack of perforated trays therein, an ante-chamber at each end of the drying chamber, such ante-chambers communicating on one side with the exterior of the drying chamber and on the other side with the exterior air, gates controlling the exterior air ports of said ante-chambers, fans adapted to cause currents of air to pass 100 through said ante-chambers and said drying chamber, an elongate air passage way connecting said ante-chambers with the exterior air, gates controlling the admission of air from the exterior into said passage way, the latter gates being located at the opposite ends of said passage way, other gates controlling the admission of air from said passage way into said ante-chambers respectively, means for heating the air in said passage way, an auxiliary air passage 105 con- 110

120

125

130

necting said ante-chambers and provided with air ports between the trays into the drying chamber, gates in the ends of the auxiliary passage way adapted to control 5 the passage of air therethrough, and automatic means adapted to operate said gates relatively to the predetermined movement of the air, and in time therewith to control the action of the devices for effecting the movement 10 of the air through said drying chamber.

8. A dehydrator or drier comprising a drying chamber, a stack of perforated trays 15 therein, an ante-chamber at each end of the drying chamber, such ante-chambers communicating on one side with the exterior of the drying chamber and on the other side with the exterior air, gates controlling the exterior air ports of said ante-chambers, fans 20 adapted to cause currents of air to pass through said ante-chambers and said drying chamber, air distributing means between said ante-chambers and the drying chamber, an elongate air passage connecting said ante- 25 chambers with the exterior air, gates controlling the admission of air from the exterior into said passage way, the latter gates being located at the opposite ends of said 30 passage way, other gates controlling the admission of air from said passage way into said ante-chambers respectively, means for heating the air in said passage way, an auxiliary air passage connecting said ante-chambers and provided with air ports be- 35 tween the trays into the drying chamber, gates in the ends of the auxiliary passage way adapted to control the passage of air therethrough, and automatic means adapted to operate said gates relatively to the pre-

determined movements of the air, and in time therewith to control the action of the devices for effecting the movement of the air through said drying chamber.

9. A dehydrator or drier comprising a drying chamber, a stack of perforated trays 45 therein, an ante-chamber at each end of the drying chamber, such ante-chambers communicating on one side with the exterior of the drying chamber and on the other side with the exterior air, gates controlling the 50 exterior air ports of said ante-chambers, fans adapted to cause currents of air to pass through said ante-chambers and said drying chambers, air distributing means between said ante-chambers and the drying chamber, 55 an elongate air passage way connecting said ante-chambers with the exterior air, gates controlling the admission of air from the exterior into said passage way, the latter gates being located at the opposite ends of said 60 passage way, other gates controlling the admission of air from said passage way into said ante-chambers respectively, means for heating the air in said passage way, a screen in each end of said air passage way, through 65 which the air passes from the latter into the adjacent ante-chamber, an auxiliary air passage connecting said ante-chambers and provided with air ports between the trays into the drying chamber, gates in the ends of the 70 auxiliary passage way adapted to control the passage of air therethrough, and automatic means adapted to operate said gates relatively to the predetermined movement of the air, and in time therewith to control the 75 action of the devices for effecting the movement of the air through said drying chamber.

DUDLEY P. POWER.
